UNITED STATES PATENT OFFICE

138,786

DESIGN FOR A VASE OR SIMILAR ARTICLE

Agnes E. Thienhaus, Milwaukee, Wis.

Application June 21, 1944, Serial No. 114,107

Term of patent 7 years

(Cl. D29—28)

To all whom it may concern:

Be it known that I, Agnes E. Thienhaus, a citizen of the United States and resident of Milwaukee, in the county of Milwaukee and State of Wisconsin, have invented a new, original, and ornamental Design for a Vase or Similar Article, of which the following is a specification, reference being had to the accompanying drawing, forming part thereof.

The figure is a perspective face view of the vase or similar article.

I claim:

The ornamental design for a vase or similar article, as shown.

AGNES E. THIENHAUS.
